UNITED STATES PATENT OFFICE.

CHARLES A. MAY, OF TRENTON, NEW JERSEY.

DESIGN FOR A EWER.

SPECIFICATION forming part of Design No. 21,591, dated May 31, 1892.

Application filed April 14, 1892. Serial No. 429,222. Term of patent 3½ years.

To all whom it may concern:

Be it known that I, CHARLES A. MAY, a citizen of the United States, residing at Trenton, in the county of Mercer and State of New Jersey, have invented and produced a certain new and original Design for a Ewer, fully described and represented in the following specification and the accompanying illustrations forming a part of the same.

10 In the accompanying illustrations, Figure 1 is a front view of the ewer, and Fig. 2 is a side view thereof.

15 The following are the leading features of the design. The body of the ewer is proportionately large and is oval in horizontal section, while the neck and mouth are somewhat elongated from front to back and the body and neck have a slight forward pitch from the foot. The neck is somewhat flattened at 20 the front and back, and the mouth is curved, as shown in Figs. 1 and 2. On the sides of the ewer is a scroll ornamentation in low relief, which springs from the foot of the ewer

near the front and back and nearly meets below the neck, leaving the greater portion of the sides with a smooth surface. On the sides of the neck of the ewer and toward the front and back is a shell ornamentation in low relief, while just below the mouth or top of the ewer is a relief-scroll decoration. The 25 handle is ornamental and bears scroll forms, as shown in Fig. 2. The flattened front of the neck and spout is slightly raised from the rounded portion of the neck and body contiguous thereto, thus producing a slight panted effect, and is relieved with slight vertical corrugations at its lower end. The foot of the ewer also shows slight vertical relief-lines.

What I claim is—

15 The design for a ewer, substantially as shown.

CHARLES A. MAY.
